TYPE POSITIONING MECHANISM

Lawrence S. Williams, Toledo, Ohio, assignor to Toledo Scale Company, Toledo, Ohio, a corporation of New Jersey

Application February 15, 1956, Serial No. 565,677

5 Claims. (Cl. 101—99)

This invention relates to printing devices and in particular to means for positioning a plurality of type-bearing wheels in a printing station.

The principal object of this invention is to provide means for accurately rotating type wheels into printing position.

Another object of the invention is to provide spring means for returning the type wheels to their original positions at the end of a printing operation.

A further object of the invention is to provide means for aligning the type wheels in their printing positions, which aligning means also prevents movement of the type wheels during the printing operation.

Other objects and advantages will be apparent from the following description in which reference is had to the accompanying drawings.

According to the invention, a plurality of type wheels are operatively connected to columns of keys on a keyboard. Depression of a selected key in each column rotates the type wheels to move the wheels to positions corresponding to the keys depressed. Each wheel has printing characters around half of its periphery and is notched on its other half, there being a notch for each printing character. After the type has been set up by the keys, a handle is operated and causes centering means to engage one notch of each wheel to correctly align the wheels and prevent their movement during the printing operation. At the end of the printing cycle, the centering means disengages from the notches in the wheels and the wheels are returned by the spring means to their original positions.

In the drawings:

Figure I is a view in side elevation of a printing weighing scale embodying the invention.

Figure II is an enlarged view, partly in section, of the keyboard and type wheels shown in Figure I.

Figure III is a fragmentary view taken substantially along line III—III of Figure II.

Figure IV is an oblique view of one of the type wheels illustrating the spring means for returning the type wheel to its original position with respect to its axle at the end of a printing cycle.

Figure V is an enlarged view taken substantially along line V—V of Figure II, parts being broken away and parts shown in section.

Figure VI is an elevational view of a modified centering means which may be substituted for the centering bar structure shown in Figure III.

Figure VII is an enlarged perspective view of the centering means shown in Figure VI.

These specific figures and the accompanying description are intended merely to illustrate the invention but not to limit its scope.

A printing weighing scale 1 embodying the invention comprises a base 2 and a housing 3 surmounting a rear portion of the base. A platter 4 is operatively connected to a disk chart 5 by means of automatic load counter-balancing mechanism (not shown) located within the

2

housing 3. The chart 5, in response to loads placed upon the platter 4, moves raised printing characters carried on a marginal area of the chart into a printing station. The raised printing characters on chart 5 correspond respectively to the weights of various loads placed upon the platter 4.

A price ring 6 lying in a plane which is angular with respect to the plane of the chart 5 has raised printing characters on a beveled face which characters correspond respectively to selected prices per pound at which articles being weighed on the platter 4 are to be sold.

A plurality of adjacent type wheels 7 lie in parallel planes which are perpendicular to the plane of the chart 5. Each of the type wheels is individually operable in response to depression of a key 8 mounted on a keyboard 9. The keys 8 are operatively connected to the type wheels 7 by means of cords 10, one for each type wheel 7. The weighing scale has a computing cylinder chart of well known construction (not shown) mounted 20 coaxially with the chart 5. When the value of an article on the platter 4 computed at a previously set up price is indicated to the operator in the well known manner, he depresses selected ones of the keys 8 to set up the indicated value of the article on the type wheels 7. An imprint of the weight, price, and value of the article on the platter 4 then may be recorded on a ticket 11, which upon pivotal movement of a handle 12 moves into juxtaposition with the printing characters on the wheels 7, price ring 6, and chart 1 where an imprint may be made 30 upon the ticket 11 by printing mechanism (not shown).

Referring now to Figure II, the type wheels 7 are journaled on bushings 13, the bushings in turn being sleeved over an axle 14. The axle 14 is threaded at both ends to receive a pair of nuts 15 which act to clamp 35 the bushings together on the axle. The bushings cannot rotate on the axle 14 because of their being clamped by the nuts 15. Rotation of the wheels 7 is therefore around the bushings. A pair of arms 16 is engaged around the opposite ends of the axle 14 outside the nuts 15. The axle 14 is clamped with respect to the arms 16 by means of nuts 17 on the outer ends of the axle.

Rotation of the type wheels 7 is brought about by depression of the keys 8, which keys are operatively connected to pivotal arms 18. Depression of selected keys 45 causes the pivotal arms to pull on the cords 10 which are wrapped more than halfway around hub-like shoulders 19 on the type wheels 7. Pivotal movement of an arm 18 therefore causes the type wheel operatively connected to that arm to be rotated to set up in printing 50 position a type character corresponding to the key 8 which was depressed.

Referring to Figure III, a link 20 is adapted to be pulled downwardly when the handle 12 is operated. A stirrup 21 is resiliently connected to the upper end of the link 20 by means of a spring 22. The stirrup is connected to a radially extending arm 23 fixed to a pivotal shaft 24 on which are carried guides 25 for the cords 10. When the link 20 is pulled downwardly as the arm 23 is operated (from the position shown in dotted lines to the position shown in solid lines in Figure III), the stirrup 21 rocks the arm 23 on the shaft 24 and causes a pair of arms 26 to rock also. A centering bar 27 mounted between the arms 26 engages in certain of a series of notches 28 which extend around approximately one half of the periphery of each of the type wheels 7. When the printing operation takes place in response to operation of the handle 12, the wheels 7 are prevented from rotating on the bushings 13 by the centering bar 27 engaging a notch of each wheel 7. The spring 22 is provided to prevent damage by the centering bar 27 to the 70 wheels 7 when the link 20 overtravels.

Each type wheel 7 has a spiral spring 29 enclosed

in a recess in the type wheel with one of its end connected to the bushing 13 and the other end connected to the type wheel. The springs are provided to resiliently urge the wheels toward their original positions to maintain the cords 10 under tension. Thus, except when held by the centering bar 27, the wheel positions always correspond with the depressed keys.

Referring now to Figure V, the keys 8 are arranged on the keyboard 9 in four columns. One column is provided for each type wheel 7. Bars 30 mounted in the keyboard 9 are adapted to be operated by the keys in the column overlying the bar. Depression of a key will pivot its bar on an axis parallel to its length through an arc corresponding to the key selected. The arm 18, fixed to the bar, pulls on the cord 10 connected to the arm and thereby rotates the type wheel on the opposite end of the cord according to the key depressed. The bars 30 are urged toward the keys by means of springs 31. When the keys are depressed, latch bars 32, one for each column of keys, catches a collar 33 on each depressed key to hold them down until a latch releasing arm 34 operatively connected, by means of a cord 35, to printing mechanism which in turn is driven by the handle 12 releases all of the depressed keys. The latch bars 32 are urged toward the keys with which they cooperate by means of springs 36, one for each bar 32.

To prevent damage to the cords 10 should the keys be punched with too much force, a tension spring 37 is inserted between each cord 10 and the corresponding arm 18 so that the sudden impacts will be absorbed by the springs 37. If such springs were not provided and a key was punched too hard, its wheel would spin beyond the selected position. Although it would return to the selected position after having passed it, the overshooting of the wheels could cause damage to the spiral spring 29 and the cords 10.

In operation, when the value of an article on the platter 4 has been determined, proper keys 8 are punched by the operator to set up the type on the wheels 7 so that the value of the article will be printed on the ticket 11 along with the weight and the price at which the article sells. One key in each column is depressed. The depressed keys are held in such depressed positions by the latch bars 32 until the handle 12 is operated and the centering bar 27 engages in the notches 28 to align and lock the wheels 7. After the centering bar has been engaged, the cord 35 operates the latch releasing arm 34 to cause the latch bars 32 to release the collars 33 and return the keys to their non-depressed positions by means of springs 38 around the keys. The wheels remain held in position by the centering bar 27 until an imprint of the characters has been made upon the ticket 11. When the latch releasing arm 34 causes the keys 8 to be released, the bars 30 are urged to their original positions by the springs 31. This may cause the arms 18 to create a small amount of slack in the cords 10. Shrouds 39 prevent the cords from slipping from the pulleys around which they pass when there is slack in the cords.

When the handle 12 is returned to its original position, the centering bar 27 releases the wheels 7, and the spiral springs 29 return the wheels to their original positions. The slack in the cables is taken up when the wheels return to their non-operated positions. An imprint has now been made on the ticket 11 of the weight, price, and value of the article on the platter 4, and the scale is ready for subsequent operations.

The centering bar 27 is a satisfactory means for aligning or centering the type wheels 7 in their printing positions and for preventing movement of the type wheels during the printing operation when the notches 28 in the type wheels are of the same size and depth and when the type wheel axle 14 is parallel to the shaft 24 about the axis of which the centering bar 27 is rocked.

However, when the notches 28 in the type wheels 7 are of different sizes and depths and/or the axes of the axle 14 and of the shaft 24 are not parallel, as may occur in mass production manufacturing, it is impossible for the centering bar to align the type wheels so that they may print a straight line of numerals. That is, the single pawl finger on the centering bar 27 cannot perfectly align the notches on four separate wheels unless the bottoms of four equally sized notches extend in a straight line that is parallel to the single pawl finger.

A modified centering means which is illustrated in Figures VI and VII may be substituted for the centering bar 27. The modified centering means provides automatic compensation for different depths in the notches 28 in the type wheels 7 and is adjustable to accommodate non-parallel axle 14 and shaft 24 axes.

The modified centering means includes a bell crank 40 having an arm 41, which corresponds exactly in structure and function to the arm 23 hereinbefore described, and a pair of arms 42 which corresponds to the pair of arms 26 hereinbefore described. When the bell crank 40 is substituted for the centering bar structure, which includes said arms 23 and 26, the stirrup 21 is pivotally connected in a hole 43 in the arm 41 of the bell crank 40 and the shaft 24 is located in a pair of holes 44 in the bell crank 40.

The pair of arms 42 of the bell crank 40 are spaced apart by an integrally formed body portion 45 upon which are mounted four spring pawls 46, there being an individual pawl 46 for each of the type wheels 7. Each of the spring pawls 46 has a notched end 47, a type wheel-centering finger 48, a slot 49, and a bent end 50. Screws 51, one for each of the pawls 46, extend through the body portion 45 of the bell crank 40 and through notches in the notched ends 47 of the pawls and are threaded into an elongated nut 52 which is common to all of the screws. The nut 52 presses all of the notched ends 47 of the pawls 46 against the body portion 45 of the bell crank and holds the pawls in place. Pivotal movement of the pawls 46 about the axes of the screws 51 is limited by means of pins 53 that are mounted on the body portion 45 of the bell crank and that protrude through the slots 49 in the pawls. Only the notched ends 47 of the spring pawls 46 are fixed in place so that the bent ends 50 of the pawls are free resiliently to move back and forth toward or away from the body portion 45 of the bell crank 40, the body portion 45 being recessed beyond the point where the nut 52 holds the pawls 46 to permit such movement. When the bell crank 40 is rocked toward the type wheels 7, the fingers 48 on the individual spring pawls 46 engage notches 28 in the type wheels. The fingers 48, because of the resiliency of the pawls 46 and because of the manner in which the pawls are mounted, automatically find the bottoms of their respective notches, any finger which happens to find a shallow or small notch being bent back toward the recessed body portion 45 of the bell crank 40. The fingers 48 on the pawls align or center the type wheels 7 in their printing positions and prevent movement of the type wheels during the printing operation. The modified centering means causes the type wheels 7 to print a straight line of numerals even though the notches 28 are of various sizes and depths. Hence, close tolerance in the forming of the notches 28 in the type wheels 7 is not necessary.

Another important feature of the modified centering means, which includes the individual spring pawls 46, is the fact that each spring pawl is individually adjustable to accommodate non-parallel axle 14 and shaft 24 axes. The single pawl finger on the centering bar 27 cannot perfectly align the notches in a plurality of separate wheels unless the bottoms of the notches extend in a straight line that is parallel to the single pawl finger. 75 In the modified structure, if after assembly in the fac-

tory or after servicing in the field, the type wheels 7 do not print a straight line of numerals because of a non-parallel relationship between the axes of the axle 14 and the shaft 24, any one or all of the screws 51 may be slightly loosened and any one or all of the pawls 46 thereafter may be shifted toward or away from the screws 51. The pawls 46 may be manually shifted by grasping their bent ends 50 with a pair of pliers. The exact location of the pawls 46 is determined by trial and error printing until the type wheels 7 print in a straight line.

There is thus provided centering means having an individual pawl for each of the type wheels 7 which individual pawl resiliently and automatically finds the bottom of the notch in the wheel mated therewith, thus, automatically compensating for different sizes and depths in the notches in the wheel, and which individual pawl is adjustable relative to every other pawl in the centering means to accommodate non-parallel axle 14 and shaft 24 axes.

The embodiments of the invention herein shown and described are to be regarded as illustrative only, and it is to be understood that the invention is susceptible to variation, modification, and change within the spirit and scope of the subjoined claims.

This application is a continuation-in-part of application Serial No. 328,551, filed December 30, 1952 and now abandoned.

Having described the invention, I claim:

1. In a type positioning device, in combination, a keyboard, a plurality of columns of keys on said keyboard, a plurality of type wheels rotatable on an axle and each having a series of raised printing type and a series of notches positioned with respect to the raised printing type, a cord drive operatively connecting each wheel to a column of keys, the keys of each column being adapted to selectively position the cooperating wheel to an approximate printing position, and centering means adapted to engage one of the plurality of notches on each wheel to accurately align the wheels during a printing operation.

2. A device according to claim 1 in which each wheel is connected to its mounting by means of a multiple-turn spiral spring.

3. In a type positioning device, in combination, a keyboard, at least one column of depressible keys on said keyboard, at least one type-bearing, pulley-like wheel having a series of raised printing type and a series of notches positioned with respect to the raised printing type, the wheel having a laterally extending hub, a cord attached to the wheel and wrapped around the hub for operatively connecting the wheel to the keys, depression of a selected key rotating the wheel through the cord to present selected type on the wheel in an approximate printing position, and centering means adapted to engage one of the plurality of notches on the wheel to accurately align the wheel during a printing operation, said centering means being released after an impression of the type has been taken.

4. In a device adapted to move type into printing position, in combination, a keyboard, a plurality of columns of keys on said keyboard, a plurality of type-bearing, pulley-like wheels each having a series of raised printing type and a series of notches positioned with respect to the raised printing type, each wheel having a laterally extending hub, an axle on which the wheels are rotatably mounted, said wheels lying in adjacent parallel planes, a cord attached to each wheel and wrapped around its hub for operatively connecting each wheel to a column of keys, depression of a key rotating the wheel operatively connected to its column to present type in an approximate printing station, and centering means adapted to engage one of the plurality of notches on each wheel to finally align the wheels during a printing operation.

5. A device according to claim 4 in which each wheel is connected to the axle by means of a multiple-turn spiral spring.
